UNITED STATES PATENT OFFICE.

ALBERT GROUT, OF SAULT STE. MARIE, MICHIGAN.

EXCAVATING BUCKET.

Application filed December 15, 1925. Serial No. 75,600.

This invention relates to an improvement in excavating buckets of the so-called "clam shell" bucket.

The object of the invention is to provide an excavating bucket of this character embodying a novel organization for opening and closing the sections of the bucket and wherein reeving of the closing cables is simplified and the entire organization rendered compact with the advantage that the bucket has a wide spread and a diminished height, thereby making it possible to work in close quarters where there is very little head room.

A further object resides in the provision of an excavating bucket having these advantages and in which the closing cable reeving provides for a powerful closing action.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a plan view of an excavating bucket embodying the present invention, the bucket being shown in open position.

Figure 2 is a view thereof in side elevation of the bucket as shown in Figure 1.

Figure 3 is a longitudinal sectional view;

Figure 4 is a diagrammatic perspective view showing the reeving of the cables;

Figure 5 is a sectional view similar to Figure 3 but showing the bucket in closed position, and

Figure 6 is an end elevational view of the bucket showing the same closed.

Referring to the drawings it will be seen that the embodiment of the present invention comprises a pair of sections, designated at 1 and 2. The sections 1 and 2 are of identical construction and each includes sides 3, bottoms 4 extending between the sides and back walls 5 connected to the bottoms 4 and also extending between the sides. Wearing shoes 6 are provided on the bottoms and sides around the meeting edges of the bucket. The sides 3 of the sections taper toward their upper ends and these small upper ends of the

sides are pivotally mounted on a pivot shaft 7 held against axial displacement by nuts 8. In this way the sections are pivotally connected to each other.

Means is provided for closing the sections 55 1 and 2 of the bucket and consists of a single closing cable 10 reeved around sheaves 11, 12, 13 and 14 and an idler sheave 15. The sheaves 11 and 12 are mounted on the section 1; the sheaves 13 and 14 on the section 2 60 and the sheave 15 on the pivot shaft 7. For the purpose of mounting the sheaves 11 and 12 on the section 1 of the bucket and the sheaves 13 and 14 on the section 2 thereof, a cross member 16 of channel cross section is 65 extended between and secured to the side walls 3 of each section of the bucket. Spaced bracket plates 17 are also provided and have lugs 18 secured to the cross members 16 and offset upper end portions 19 provided with 70 openings in which the shaft 7 is rotatably fitted. The bracket plates 17 are held against displacement on the shaft 7 by means of spacing sleeves 20. The pulleys 11, 12, 13 and 14 are rotatably mounted on the bracket 75 plates 17 by means of pulley shafts 21 mounted on these bracket plates. The pulleys 11 and 12 are spaced from each other by means of a spacing plate 22 held in position by a cotter pin 23. A similar spacing plate 80 24 and cotter pin 23 space the pulleys 13 and 14. In both instances the cotter pin engages the bracket plates to hold the spacer plates against displacement. The idler sheave 15 is rotatably mounted on the shaft 7 between 85 the upper end portions of the bracket plates 17. One end of the closing cable 10 is anchored, as at 26, to the axis 21 of the pulleys 13 and 14. The closing cable then extends across the bucket and is reeved under and over the pulley 12, then extended back across the bucket and reeved under and over the pulley 14, then back across the bucket and under and over the pulley 11, then again back across the bucket and under and over the pulley 13. After leaving the underside of the pulley 13 the cable 10 is extended back to the center of the bucket and is reeved around the idler pulley 15.

An important feature of the invention re- 100

sides in the fact that the operating sheaves; that is, the sheaves 11, 12, 13 and 14 are provided only on the sections of the bucket and that the operating or closing cable 10 is directly reeved around the sheaves. This is one of the main features which contributes largely to the capacity of the bucket to have a maximum spread and the minimum height in open position whereby it is adapted to deal effectively with the material and to be operated even in close quarters and where there is very little head room.

Means is provided for opening the sections of the bucket and consists in general 15 of a cable and pulley operated toggle. The toggle is made up of two pairs of links, the links of each pair being designated at 30 and 31. Each link 30 is pivotally mounted at one end on a transverse supporting shaft 32 20 having its ends mounted on the sides 3 of the sections 1 of the bucket and having its intermediate portions extended through the bracket plates 17. The links 31 are similarly pivotally supported on a shaft 33 which 25 is carried by the sides 3 and bracket plates 17 of the section 2 of the bucket. The links 30 and 31 are also pivotally connected together by means of a pivot shaft 34 which extends through pivot openings in the lower 30 ends of the links and which is held against displacement by means of nuts 35. The pivot shaft 34 is located in the center of the bucket and in vertical alignment with the axis of the shaft 7 in all positions and phases 35 of operation.

With this arrangement when the shaft 34 is pulled upwardly toward the shaft 7 the links of the toggle force the sections 1 and 2 of the bucket to open position and on the 40 other hand when the shaft 34 moves downwardly away from the shaft 7 the links of the toggle permit the sections 1 and 2 to approach each other and eventually to come to the closed position shown in Figure 5.

45 For the purpose of imparting these movements to the shaft 34, pulley or sheave assemblies 36 and 37 are mounted on the shaft 34 and cables 38 and 39 are trained around the loose rotating pulleys of these assemblies. 50 One end of the cable 38 is anchored, as at 40, on a lug 41 integrally formed with one of the bracket plates 17 and the other cable 39 has one end similarly anchored to a lug 42 provided on another plate 17. The cables 55 38 and 39 are oppositely disposed in respect of the direction in which they extend around their pulleys but both of these cables have an end anchored to a cross bar 43 carried by the main opening cable 44.

60 With this arrangement when the tension on the closing cable 10 is slackened and the cable 44 is taken up the cables 38 and 39 are pulled upwardly to elevate the pulleys 36 and 37 and consequently to draw the shaft 65 34 up toward the shaft 7, thereby causing the

toggles to open the sections of the bucket as illustrated to advantage in Figures 2 and 3. In this position the bucket is lowered onto the material to be hoisted or excavated and after the bucket has been dropped onto or 70 engaged with this material the tension on the cable 44 is slackened and the cable 10 is taken up by the engine which effects a closing of the sections of the bucket in a powerful manner.

75 When pivot shaft 34 is drawn upward toward pivot shaft 7, shaft 34 comes up against lower side of bracket 40^a when bucket is at its maximum opening and holds it from any wider opening.

I claim:—

1. In a clam shell bucket, a pair of bucket sections each having extensions in longitudinal alignment with the sides of the sections, a pivot shaft connecting the free ends of the extensions of both sections, a cross member connecting the sides of each section at the base of said extensions, a pair of laterally spaced bracket plates secured to each cross member with their upper ends engaged with said pivot shaft, a pulley shaft mounted between each pair of plates adjacent the cross member of each section, a pair of pulleys carried by each pulley shaft, and a single closing cable anchored at one end to a pulley on one section and reeved around the pulleys of both sections extending directly without deflection from the pulleys of one section to the pulleys of the other section, the bucket sections being adapted to open out into longitudinal alignment and in alignment with their supporting pivot when in open position, thereby adapting the bucket to have a maximum spread with a minimum height in open position.

100 2. In a clam shell bucket, a pair of bucket sections each having extensions in longitudinal alignment with the sides thereof and tapering toward their upper ends, a pivot shaft connecting the free ends of said extensions, a cross member connecting the sides of each section at the base of said extensions, a pair of laterally spaced bracket plates secured to each cross member with their upper ends inwardly offset and engaged with the pivot shaft, spacing sleeves on said shaft to hold said plates against displacement, a pulley shaft mounted between each pair of plates adjacent the cross member, a pair of pulleys carried by each pulley shaft, and a single closing cable anchored to one section and reeved around the pulleys of both sections, being reeved from pulleys in one section directly to those of the other section without deflections from the pulleys of one section to the pulleys of the other, and an idler pulley carried by the pivot shaft around which said cable passes after being reeved around the pulleys of the two sections.

105 3. In a clam shell bucket a pair of bucket

sections, each having side plates with extensions in longitudinal alignment therewith, a pivot shaft connecting the free ends of said extensions, a cross member connecting the sides of each section at the base of said extensions, a pair of laterally spaced bracket plates secured to each cross member with their upper ends engaged with said pivot shaft, a pulley shaft mounted between each

pair of plates adjacent the cross members, a 10 pair of pulleys carried by each pulley shaft, a single opening cable anchored to one section and reeved around the pulleys of the two sections without deflection, and toggle means connected with said side plates for 15 opening the bucket sections.

ALBERT GROUT.
